US00D740775S

(12) **United States Design Patent**
Joung et al.

(10) **Patent No.:** **US D740,775 S**
(45) **Date of Patent:** **** Oct. 13, 2015**

(54) **MOBILE PHONE**

(71) Applicant: **LG ELECTRONICS INC.**, Seoul (KR)

(72) Inventors: **Joungyoung Joung**, Seoul (KR);
Woonlee Park, Seoul (KR); **Joonhyung Kim**, Gyeonggi-do (KR)

(73) Assignee: **LG Electronics Inc.**, Seoul (KR)

(**) Term: **14 Years**

(21) Appl. No.: **29/477,803**

(22) Filed: **Dec. 27, 2013**

(30) **Foreign Application Priority Data**

Jun. 28, 2013 (KR) 30-2013-0033570

(57) **CLAIM**

The ornamental design for a mobile phone, as shown and described.

DESCRIPTION

FIG. 1 is a rear perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view thereof;

FIG. 9 is a rear perspective view thereof showing the state that the battery cover has been opened; and,

FIG. 10 is a rear perspective view thereof showing the state that the small LCD display below the rear camera part disappears when the mobile phone is turned off.

The broken lines shown in the figures that are immediately adjacent to the shaded areas and define unshaded regions represent boundaries of the claim while the broken lines within the broken line boundaries show portions of the mobile phone that form no part of the claimed design; the broken lines form no part of the claimed design.

1 Claim, 9 Drawing Sheets
